UNITED STATES PATENT OFFICE.

G. RALSTON AYRES, OF PHILADELPHIA, PENNSYLVANIA, ASSIGNOR TO
WILLIAM AYRES AND G. RALSTON AYRES, OF SAME PLACE.

DESIGN FOR A FABRIC FOR HORSE-BLANKETS.

Specification forming part of Design No. **7,804**, dated October 20, 1874; application filed October 7, 1874.
[Term of Patent 3½ years]

To all whom it may concern:

Be it known that I, G. RALSTON AYRES, of Philadelphia, Pennsylvania, have invented or produced a Design for a Horse-Blanket, of which the following is a specification:

Sufficient of my design for a horse-blanket is shown in the accompanying drawing to illustrate the same, the remainder being merely a repetition of that which appears.

The main features of the design are the double stripes *a a* and *b b*, of different colors, forming squares, the squares formed by one set of stripes being so arranged in respect to those formed by the other set as to inclose spaces *c*, and a series of squares formed by narrow stripes *d d* are so arranged in respect to those formed by the wide stripes as to di-

vide the spaces *c* into smaller spaces, all as clearly shown in the drawing.

Irrespective of the particular colors employed, I claim—

1. The design for the double stripes *a a* and *b b*, of different colors, and arranged as described, and as illustrated in and by the accompanying drawing.

2. The design for the whole blanket, including the stripes *a a*, *b b*, and *d d*.

In testimony whereof I have signed my name to this specification in the presence of two subscribing witnesses.

G. RALSTON AYRES.
